UNITED STATES PATENT OFFICE.

ELLEN E. WEED, OF BROOKLYN, NEW YORK.

STRAINER FOR SINKS.

SPECIFICATION forming part of Letters Patent No. 728,059, dated May 12, 1903.

Application filed July 24, 1902. Serial No. 116,787. (No model.)

To all whom it may concern:

Be it known that I, ELLEN E. WEED, a citizen of the United States, residing at Brooklyn, in the county of Kings and State of New York, have invented certain new and useful Improvements in Strainers for Sinks, of which the following is a full and complete specification, such as will enable those skilled in the art to which it appertains to make and use the same.

This invention relates to the ordinary strainer located at the mouth of the waste-pipe of a sink; and the object of the invention is to provide an improved device of this class which may be easily and conveniently cleaned at all times and also easily and conveniently removed or detached, so as to afford access to the waste-pipe for cleaning or other purposes; and with these and other objects in view the invention consists of a strainer for sinks constructed as hereinafter described and claimed.

The invention is fully disclosed in the following specification, of which the accompanying drawings form a part, in which the separate parts of my improvement are designated by the same reference characters in each of the views, and in which—

Figure 1 is a top plan view of my improved strainer detached from the sink; Fig. 2, a bottom plan view thereof; Fig. 3, a transverse section on the line 3-3 of Fig. 1 and showing the device applied to the bottom of a sink.

In the drawings forming part of this specification I have shown at *a* the bottom of an ordinary kitchen or other sink, which is provided with an annular depressed portion *a*², having an inwardly-directed annular flange or rim *a*³, which forms the opening *a*⁴ in the bottom of the sink. I have also shown at *b* the ordinary escape-pipe of the sink, and in the form of construction shown this pipe is provided at its upper end with an enlargement *b*², having a flange or rim *b*³, which is bolted, screwed, or otherwise secured to the bottom of the flange or rim *a*³, as clearly shown at *b*⁴ in the drawings.

In the practice of my invention I mount on the countersunk flange or rim *a*³ at the bottom of the sink an annular plate *c* and which in the form of construction shown is secured to said flange or rim by screws *c*²; but this con-

nection may be made in any desired manner. Above the annular plate *c* I place a strainer-plate *d*, the top surface of which is flush with the bottom surface of the sink, and the strainer-plate *d* is detachably connected with the annular plate *c*, and in order to accomplish this result I form in the strainer-plate *d*, near the perimeter thereof, T-shaped slots *d*² and *d*³ connect with the annular plate *c* pins or other suitable devices *d*³, having oblong heads *d*⁴, which are adapted to pass through the heads of the T-slots *d*², and when the strainer-plate *d* is turned the pins *d*³ enter the longer portion of the T-slots, as shown in Fig. 1, and the strainer-plate *d* is detachably locked to the annular plate *c*. The strainer-plate *d* is provided with radial rows of perforations *d*⁵, and connected with the bottom of said plate centrally thereof by means of a pivot-pin *e*² is a valve-plate *e*², having radial slots or openings *e*³. The strainer-plate *d* is also provided with a segmental slot *d*⁶, and the valve-plate *e*² is provided with a corresponding pin *e*⁴, which passes through said segmental slot, and by means of the pin *e*⁴ the valve-plate *e*² may be turned so that the radial slots *e*³ therein will register with the perforations *d*⁵ in the plate *d*, as indicated in full lines in Fig. 2, or said valve-plate may be turned so that said slots will not register with said perforations, as is also indicated in Fig. 2.

The plates *d* and *e*² are both circular in form, and the plate *e*² is placed within the annular plate *c*, and in practice the pin *e*⁴ is secured in the valve-plate *e*², so that it will not become detached therefrom, or said pin may be formed integrally with said plate, and this is also true of the pins *d*³, which may be secured in or to the annular plate or be formed integrally therewith. As thus constructed it will be seen that the strainer-plate, with the valve-plate secured thereto, may be detached whenever desired for cleaning or other purposes or may be quickly and easily replaced in position whenever necessary.

Having fully described my invention, what I claim as new, and desire to secure by Letters Patent, is—

A sink, the bottom of which is provided with an escape-pipe opening around which is a countersunk annular flange or rim, an annular plate secured on said annular flange or

rim, a strainer-plate detachably connected with said annular plate, and a valve-plate connected with the bottom of the strainer-plate centrally thereof and within said annular plate, said valve-plate being provided with a pin which passes upwardly through a segmental slot formed in the strainer-plate, said valve-plate being also provided with perforations or openings corresponding with similar perforations or openings in the strainer-plate and adapted to register therewith, and means

for operating the valve-plate through the strainer-plate, substantially as shown and described.

In testimony that I claim the foregoing as my invention I have signed my name, in presence of the subscribing witnesses, this 23d day of July, 1902.

ELLEN E. WEED.
